Primary Examiner — Catherine R Oliver-Garcia*(74) Attorney, Agent, or Firm* — Boudwin Intellectual Property; Daniel Boudwin(57) CLAIM

The ornamental design for a pocketed holster, as shown and described.

DESCRIPTION

FIG. 1 is a perspective view of a pocketed holster, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The shade lines in the Figures show contour and not surface ornamentation.

The broken lines in FIG. 1 form no part of the claimed design.
